ATTORNEY.

UNITED STATES PATENT OFFICE

111,684

DESIGN FOR A RUG OR SIMILAR ARTICLE

Henry J. Muller, Lancaster, Pa., assignor to Armstrong Cork Company, Lancaster, Pa., a corporation of Pennsylvania

Application August 23, 1938, Serial No. 79,504

Term of patent 7 years

To all whom it may concern:

Be it known that I, Henry J. Muller, a citizen of the United States, residing at Lancaster, county of Lancaster, Commonwealth of Pennsylvania, have invented a certain new, original, and ornamental Design for a Rug or Similar Article, of which the following is a specification, reference being had to the accompanying drawing, forming a part thereof and in which the figure is a plan view of a rug illustrating my design.

I claim:

The ornamental design for a rug or similar article, as shown.

HENRY J. MULLER.
